UNITED STATES PATENT OFFICE.

CARL E. EKLIND AND WILLIAM W. DARROW, OF CHICAGO, ILLINOIS, ASSIGNEES TO CAMEL COMPANY, OF CHICAGO, ILLINOIS, A CORPORATION OF ILLINOIS.

METAL CAR DOOR.

Application filed December 15, 1924. Serial No. 755,825.

This invention relates to metal door constructions for freight cars.

In the manufacture of metal doors for freight cars, it is extremely important that the doors shall be sufficiently strong to resist not only the outward thrust from the contents of the car, but also the jarring and racking strains that such doors are subjected to. It is also necessary that these doors should be maintained as light as possible for ease of operation and economy of cost, and should be so supported that they may be easily operated. It is also desirable that such doors should be so constructed or equipped as to effectively exclude the weather.

It is an object of this invention to provide a car door construction that fulfills the above noted requirements, that is both strong, durable and light, that is constructed for effectively excluding the weather, that avoids unprotected joints and that is supported for easy operation and that is simple and inexpensive in manufacture.

With these and other objects in view which will become more apparent in the following description and disclosures; this invention comprises the novel structure and combinations hereinafter described and more particularly pointed out and defined in the appended claims.

In the accompanying drawings which illustrate a preferred embodiment of this invention and in which similar reference numerals refer to similar features in the different views:

Figure 1 is a fragmentary elevational view of a freight car illustrating this invention applied thereto in the form of a main door and supplemental door.

Figure 2 is an enlarged broken sectional view upon the line II—II of Figure 1.

Figure 3 is an enlarged broken sectional view upon the line III—III of Figure 1.

Figure 4 is a fragmentary front elevational view of the door illustrating the use of a corner gusset plate spot-welded to the door.

Figure 5 is a fragmentary plan view illustrating a modified manner of connecting the panel sections of the door.

Figure 6 is a sectional view upon the line VI—VI of Figure 5.

Figure 7 is a fragmentary sectional view of a modification of the front end structures of the doors.

Figure 8 is a view similar to Figure 7 of a further modification of the front end structures of the doors.

Figure 9 is a fragmentary sectional view illustrating a front end construction applicable to a single door, with a slightly modified panel.

Referring now to the drawings, it will be noted that this invention has been illustrated in connection with a freight car for hauling automobiles, furniture or the like which requires an enlarged door space which is closed by a main door 1 and a supplemental door 2 constructed in accordance with this invention.

It will be noted that each door consists of a frame comprising an upper T bar 3 connected by rear edge T bars 5, the heads of which extend at right angles to the plane of the door. The inner flange of each head is deformed by being inclined forwardly for wedging relation with the inclined face of a weather strip 6 secured to the flange of a Z bar 23 on the adjacent door post 24.

A T bar 7 connects the forward ends of the T bars 3 and 4 of the main door. The head of this T bar lies in the plane of the door and the flange thereof projects outwardly. The forward flange 7a of this head is slightly inclined and offset in an outward direction as shown in Figures 2 and 7, or merely inclined as indicated at 18 in Figures 8 and 9.

A T bar 8 connects the forward ends of the T bars 3 and 4 of the supplemental door 2. The head of this T bar lies in the plane of the door and the flange 8a thereof is directed outwardly and inclined forwardly to provide a groove or the like having an outer bevelled wall. The flange 7a of the T bar 7 is adapted to enter this groove and wedge against the outer inclined wall thereof to effectively seal the joint between the two doors for excluding the weather.

A corrugated sheet metal panel is riveted or secured to each frame. Each panel consists of a plurality, three in the present instance, of longitudinally extending sections having longitudinally extending and outwardly directed corrugations. The panel

- sections 9 of the main door have heels or flanges 11 at their ends which are formed by bending the terminal metal at right angles. These flanges fit against the outstanding flanges of the front and rear T bars and are riveted thereto thus strengthening the door structure and providing a tight joint to exclude the weather. The corrugations of these panel sections extend contiguous to the heels or outstanding flanges of the said T bars and substantially merge therein to brace or reinforce the same. It will be noted that these panel sections are also secured or riveted to the flanges of the T bars that lie in the plane of the door, so each end of each section is secured by two rows of rivets at right angles to each other. The sides of these panel sections are secured together in overlapping relation and the upper and lower sections are also secured to the upper and lower frame members. The margin of the upper panel section 10 is preferably provided with a heel 11 similar to the heels at the ends and similarly secured.
- 25 The panel sections 10 of the supplemental door may have their outer margins provided with heels 11 similar to the sections 9. The inner margins thereof are however preferably flat as shown in Figures 1 and 2.
- 30 Instead of riveting or welding the panel sections together, they may be provided with telescopic folds 11^a and 12 as shown in Figure 6. In referring to said figures, it will be noted that one panel section has its fold 35 inwardly offset to bring the outer surface of the sections substantially flush. After these folds are brought into telescopic relation they are indented as indicated at 13 to interlock the same.
- 40 If desirable, suitable gusset plates 14 may be spot-welded to the corners of the frame to increase the strength and rigidity thereof as shown in Figure 4.
- 45 The supplemental door 2 usually carries a wooden jamb 15 at its forward end which may be bolted to the front T bar as shown in Figure 2, or an additional T bar 16 (Fig. 7) may be secured to the head of the T bar 8 and the jamb secured in the forward angle 50 of said T bar 16. In the latter construction, a plate 17 is preferably applied to the side of the jamb as shown.
- 55 In Figure 8 there is shown a slight modification of the front structures of the main door and supplemental door. In referring to said figure it will be noted that the corrugations of the main door 1^a terminate short of the ends of the panel sections. The ends of the panel sections are however bent outwardly to lie along the outstanding flange of the T bar 7 to provide heels 11 and they are riveted or secured to both adjacent flanges of such T bar. The forward flange of the front T bar 7 is inclined forwardly 60 as indicated at 18. The supplemental door 2^a
- has a front angle 19 that slopes forwardly and outwardly to receive the inclined end 18 in wedging relation thereunder and to contact the outstanding flange of the T bar 7 to seal the joint between the doors for 70 excluding the weather. A movable jamb in the form of an angle bar 20 is secured to the angle 19 of the supplemental door.
- In Figure 9 there is shown a modification of the front structure of the main door when 75 no supplemental door is used. In referring to said figure it will be observed that the structure of the door 1^a is similar to that of the main door 1^a shown in Figure 8 excepting that the panel sections have their attaching ends outwardly offset as indicated at 21 to bring the inner surface of the sections flush with the back of the T bars. The front T bar 7 of this door has its forward flange 80 outwardly inclined at 18 which is adapted 85 to enter a channel formed in an angular member 22 secured to a Z bar 23 that embraces the front door post 24. The outer flange of this member 22 is outwardly inclined for wedging relation with the inclined flange 18 of the T bar 7. These doors may be supported in different ways. One way consists of suspending the same by means of roller hangers 25 which travel on a horizontal track 26 secured above the doorway. In the present instance, a single roller support is used for each door. This supporting means, however, is not claimed in 90 this application as it is made the subject 95 matter of a copending application.
- 100 It will be appreciated that the use of T bars for the door has a number of advantages. First, it has the advantage that a standard rolled member or section may be used, and the front and rear T bars may be 105 readily fabricated to provide proper deformed angles for weather proofing purposes. In the second place they impart rigidity to the door and in the third place they provide outstanding flanges against which the heels or end flanges of the panel sections may be secured. It will be noted that the end flanges on the panel sections which are secured to these outstanding flanges not only greatly increase the strength of the door, but at the same time provides a tight 110 weather sealing joint.
- 115 We are aware that many changes may be made, and numerous details of construction may be varied through a wide range without departing from the principles of this invention, and we therefore do not purpose limiting the patent granted hereon, otherwise than necessitated by the prior art.
- 120 We claim:
1. A car door comprising a frame having a rear edge T bar, the inner flange of said T bar being deformed to form a weather guard, and a panel secured to said frame.
  2. A car door comprising a frame, having 125

- a front edge **T** bar, one flange of said **T** bar being deformed to form a weather guard.
3. In a metal car door, a frame comprising lateral edge **T** bars one flange of each **T** bar being deformed to form a weather guard, and a panel secured to said frame.
4. In a car structure, the combination with a pair of sliding doors, of a pair of **T** bars, one attached to the front edge of each door, 10 a flange of one **T** bar being deformed to provide a groove, and a flange of the other **T** bar being deformed to wedgingly fit in such groove.
5. In a car structure, the combination with 15 a pair of sliding doors having meeting edges, an angular member providing a groove on one door and an angular member providing an inclined flange on the other door for wedgingly engaging in the groove of the 20 first member.
6. In a car having a door opening, a sliding door for closing said opening, said door having a front edge **T** bar, said **T** bar having a forwardly projecting outwardly inclined 25 flange and a grooved member having an outwardly inclined wall for receiving said flange.
7. In a car door, a frame including a pair 30 of **T** bars, each having an outwardly directed flange, whereby interior angular seats are formed, and a corrugated metal panel having opposed angular margins fitting in said
- angular seats, and means for securing said angular margins to both the heads of the **T** bars and to the outstanding flanges thereof. 35
8. In a car door, a sheet metal panel having a pair of opposed marginal flanges with corrugations extending between said flanges and substantially merging into the same for bracing the same, in combination with a 40 frame having angular seats in which the flanged margins are secured.
9. In a car door, a sheet metal panel having a pair of opposed marginal flanges with corrugations extending between said flanges 45 and terminally bracing the same, in combination with a frame having a pair of opposed members with angular seats in which the flanged margins of said panel are secured, and means for securing said panel to 50 both walls of each seat.
10. In a car door, a sheet metal panel having opposed angular margins with corrugations extending between and cushioning said angular margins, in combination with a 55 frame having opposed members with angular seats fitting the angular margins of the panel and means securing said panel to both faces of each seat.
- In testimony whereof we have hereunto 60 subscribed our names

CARL E. EKLIND.
WILLIAM W. DARROW.
